US00D860539S

(12) **United States Design Patent** (10) **Patent No.:** **US D860,539 S**
(45) **Date of Patent:** **** Sep. 17, 2019**

(54) **COSMETIC COMPACT**

(71) Applicant: **Mary Kay Inc.**, Addison, TX (US)

(72) Inventors: **Jenny DeMarco Staab**, Addison, TX (US); **Alexa Hanna**, Addison, TX (US)

(73) Assignee: **Mary Kay Inc.**, Addison, TX (US)

(**) Term: **15 Years**

(21) Appl. No.: **29/663,281**

(22) Filed: **Sep. 13, 2018**
